SELF-PROPELLED DIVING CHAMBER

Edwin A. Link, Binghamton, N.Y., assignor to Ocean Systems, Inc., a corporation of New York
Filed Apr. 15, 1966, Ser. No. 542,812
1 Claim. (Cl. 114—16)

ABSTRACT OF THE DISCLOSURE

A submarine useful in connection with deep sea diving operations, which has a high degree of maneuverability. The submarine has a main propulsion unit adapted to swivel 180 degrees about a vertical axis in the hull. In addition, a bow thruster and a reversible hovering motor and propeller unit are incorporated into the submarine. Aircraft-type controls are utilized to operate the three above-described propulsion units.

This invention relates to diving and to a submersible self-propelled craft and a control system for same. This invention is useful in practicing the methods disclosed in my co-pending application, Ser. No. 335,251, filed Jan. 2, 1964, entitled, "Underwater Capsule," now U.S. Patent 3,299,645.

With the increased interest in research and exploitation of the ocean bottom, a number of small submarines have been designed and built. Several of these are illustrated in Newsweek Magazine for Sept. 28, 1965, pages 84 and 85.

A submarine designed to work on the ocean bottom in the support of salvage operations and other such tasks requires a degree of maneuverability not important to military submarines that generally shun the bottom.

It is an object of this invention to provide a small submarine having improved maneuverability and full 3-axis control at zero speed. It is another object of the invention to provide simplified aircraft-type controls whereby a single pilot may flexibly control all motions of the craft. It is still another object of the invention to provide a small submarine of the lock-out type in which the personnel spaces may be supplied either with air at normal atmospheric pressure or in the alternative with a high-pressure breathing mixture, whereby the vehicle may be used to transport pressurized divers, unpressurized observers, or both, between a submarine chamber of the kind described in my co-pending application Ser. No. 335,212, filed Jan. 2, 1964, now Patent No. 3,293,676, and a tender at the surface. In such service this submarine is a free swimming version of the diving chamber disclosed in my above-mentioned "Underwater Capsule" application.

The invention accordingly comprises the features of construction of the submarine, the combination of its elements and the arrangement of parts which will be exemplified in the construction hereinafter set forth, and the scope of the invention will be indicated in the claim. A feature of the invention by which the above objects are realized is a full swiveling bow thruster rotatable 360 degrees around the longitudinal axis of the craft. Another feature of the invention is a main propulsion unit at the stern which swivels 180 degrees horizontally from port to starboard. A third feature of the invention is a stern hovering motor and propeller assembly to provide vertical control of the stern. Another feature of the invention is a control wheel assembly which is rotated to control the bow thruster and moved forward and backward to control the stern hovering motor taken together with foot pedals controlling the stern propulsion unit whereby aircraft-like controls are available for operation either in the mode of an airplane or in the mode of a

2

helicopter. A further feature of the invention is a conning tower 16 with a top hatch 28 to resist pressure from outside and an inner hatch 29 to withstand high pressure in the control chamber or from inside. A further feature of the invention, is a diving chamber 20 with double hatches connecting it to the control chamber 22 and with a double diver's hatch communicating downward into the sea. Other objects and features of the invention will be apprehended from the following detailed description taken in connection with the accompanying drawings in which:

FIGS. 1a, 1b and 1c are orthographic projections showing a general arrangement diagram of the submarine, and

FIG. 2 is a schematic diagram of the control system for the submarine.

The pressure hull of the submarine comprises a forward hull cylinder 10, a bow hemisphere 12, a diver compartment cylinder 11, a diver compartment forward hemisphere 13, a stern hemisphere 14, a transition piece 15 and a cylindrical conning tower 16. Dividing the pressure hull into pressure-tight compartments, a diving chamber 20 and a pilot's cabin 22 is the hemispheric bulkhead portion 23. Hatches 24 and 25 are closed to maintain the diver's chamber at higher than outside pressure. Hatches 26 and 27, on the other hand, are closed to maintain the diving chamber at lower than outside pressure. The top hatch 28 on the conning tower 16 is normally closed; but inner hatch 29 may be closed if a "pressurized" pilot should desire to bring the craft to the surface with high pressure in the cabin 22.

By the methods disclosed in my above-mentioned co-pending applications it is possible for divers to work for extended times at depths of 300 feet and more. A submarine of the type described therein may be based with such divers at such a depth and with the hatches as provided may be used by them to descend to still greater depths or to rise to the surface. It will be noted that when both compartments 20 and 22 are internally pressurized to, for example, 300 feet, the operating depth of the submarine is thereby extended by the same 300 feet.

Attached to the stern hemisphere is a stern fairwater 30 which provides a smooth streamlined covering for the stern of the ship. The fairwater is not water-tight and seawater ambient pressure is equalized at all times. It has cut outs 32, 34 for windows 36. Contained within this fairing is a main spherical gas flask 42 having equatorial flanges 43 at which the cylindrical and conical sections of the stern fairwater are joined. Fixed to the bottom of the craft are high-pressure gas cylinders 50. Releasably hanging between them are the main electric batteries 52 enclosed in a cylindrical pressure vessel 54. At the bow of the craft is a modified outboard motor drive unit 56 which pivots about the centerline of the hull. The drive shaft for the propeller 57 passes through a seal 58 into the hull where it is connected to be driven by an electric motor 59 within the hull. A second seal 60 carries the steering shaft 61 through the hull to a small sprocket 62. The small sprocket is connected by a stainless steel chain 63 to a larger sprocket 64 which is fixed to and turns the unit 56.

At the aft end of the stern fairwater 40 is a vent 68 extending vertically through the fairing. Located within the vent is a propeller 70 driven by a flexible shaft 71 from a motor 72, these parts comprising the stern hovering unit. Rigged aft of the stern hovering unit supported in bushings 75, 76 to rotate about a vertical axis Y—Y is the main propulsion motor 80 having a multi-bladed fully shrouded propeller 82. The thrust axis of the main motor is rotatable about the vertical axis Y—Y from starboard through dead aft to port and vice-versa under control of hydraulic actuators (not shown). The motor is enclosed by a fairing section 84 which also turns about

the axis Y—Y; however, it is spring loaded to remain aligned with the aft fairing 40 until the motor 80 and propeller 82 are turned about 20° to either side. From 20° to 90° the fairing 84 turns with the motor 80 and serves as shroud and protection for the main propulsion motor.

Access while surfaced is provided by the hatch 28 atop the conning tower 16. Deck fairings 92 and 93 are provided to improve footing and surface handling capability.

FIG. 2 illustrates schematically the controls of the craft.

The manual controls are a wheel 100 which rotates 360 degrees and slides forward and backward as a splined tube 102 telescopes over the steering shaft 61.

Turning the wheel rotates the bow thruster, normally pointed downward and a "horn" button 103 on the wheel controls the bow thruster motor. Pressing the wheel forward depresses a horizontal control surface 104 located in the wash of the main propeller 82 by means of a hydraulic cylinder 106 coupled to the tube 102 and a hydraulic actuator 108 within the fairing 40. Pressing the wheel hard forward engages an electrical contact 110 which activates the stern hovering motor 72 to raise the stern. Conversely pulling the wheel back depresses the stern by elevating control surface 104 and reversing the motor 72 through contact 111.

Foot pedals 112 and 114 through cylinders 116 and 118 and actuator 120 control the swiveling of the main motor 80 and propeller 82. Main motor speed is controlled by a throttle-like hand lever 122 forward for forward and back for reverse.

With the controls as just outlined this craft has complete controllability (except for roll) at any speed. It can move forward, backward, up, down, or sideways without turning and can turn without headway.

It will thus be seen that the objects set forth above, among those made apparent from the preceding description, are efficiently attained, and since certain changes may be made in the above constructions without departing from the scope of the invention, it is intended that all matter contained or shown in the accompanying drawings shall be interpreted as illustrative and not in a limiting sense.

It is also to be understood that the following claims are intended to cover all of the generic and specific fea-

tures of the invention herein described, and all statements of the scope of the invention which, as a matter of language, might be said to fall therebetween.

Having described my invention, what I claim as new and desire to secure by Letters Patent is:

5 A submarine comprising a hull having a bow and a stern, a main propulsion motor and propeller mounted as a unit and carried at the stern of said hull on bearings permitting swiveling 180 degrees about a vertical axis in said hull, a pair of foot pedals, control means interconnecting said foot pedals with said unit for controlling the swiveling thereof, a bow thruster comprising a motor and an auxiliary propeller mounted at said bow and rotatable about the longitudinal axis of said hull, said motor being coupled to said propeller to tune it on an axis perpendicular to said longitudinal axis whereby the thrust of said auxiliary propeller may be directed to any direction perpendicular to said longitudinal axis, a steering wheel connected to said bow thruster for rotating same about said longitudinal axis, and a hovering unit comprising a hovering propeller carried at said stern constrained to rotate on a vertical axis, a reversible motor and transmission means for driving said hovering propeller, and control means interconnecting said reversible motor with said steering wheel whereby movement of said steering wheel in a forward direction causes said reversible motor to drive said hovering propeller in one direction while movement of said steering wheel in a backward direction causes said reversible motor to drive 10 said hovering propeller in the opposite direction.
